UNITED STATES PATENT OFFICE

2,459,450

NONREFILLABLE BOTTLE

William F. Owen, Daytona Beach, Fla.

Application February 23, 1946, Serial No. 649,558

7 Claims. (Cl. 215—25)

1

The invention as described herein, and illustrated in the accompanying drawings, consists of a bottle, an object of which is to provide means whereby the same can not be refilled after the insertion of my closure therefor.

Another object of the invention is to provide a bottle closure provided with a circuitous outlet.

Another object of the invention is to provide a bottle stopper provided with an outlet passage and an air seal which will prevent refilling through the passage.

A primary object of the invention is the provision of means whereby a bottle when once filled can not be refilled with a spurious liquor.

Other features and advantages will become more readily apparent from the following description and the accompanying illustrative drawings in which:

Figure 1 is a vertical sectional view of the invention shown in upright position.

Figure 2 is a like view, the bottle being inverted.

Figure 3 is a sectional view taken on line 3—3 of Figure 1.

Figure 4 is a similar view taken on line 4—4 of Figure 1, and

Figure 5 is a sectional view taken on line 5—5 of Figure 1.

While one embodiment of the invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of the device, which is to be limited only in accordance with the appended claims. And while there is stated the primary field of utility of the invention it remains obvious that it may be employed in any other capacity wherein it may be found applicable.

In the accompanying drawings, and in the following specification, the same reference characters are used to designate the same parts and elements throughout and in which 10, refers to the invention in its entirety and 11, indicates a bottle, the neck 12 of which is provided with valve seats 13 and 14, and upon seat 13 normally rests a floating valve 15, provided with a cylindrical upper wall 16, and flat bottom and top walls 17 and 18. The wall 19, surrounding valve 15, is fluted and the space between valve seats 13 and 14, is sufficient to permit unseating of valve 15, upon

2

inverting the bottle 11, to permit liquid in the bottle to flow out around the valve.

The wall 20, surrounding valve 21, seating normally on the valve seat 14, is also fluted for permitting liquid to pass between the valve and the said wall upon inverting the bottle. Slightly above the top flat wall 22 of valve 21 is provided an annular inner groove 23, adjacent the upper end 24 of neck 12 between which groove and the seat 14 the valve 21, is movable. This valve is non-floating.

After the bottle 11 is originally filled and the valves 15 and 21 dropped into place upon their respective seats, the bottle cap 25 is forced to its seat in the upper end 24 of the bottle neck. This cap has projecting down from its lower wall 26 a series of annularly spaced fingers 27, 28 and 29, each provided with a right angular projection 30, adapted to be sprung into the annular groove 23, through the inclination of the inner beveled surface 31, forming the mouth of the bottle. The annular flange 32 of the cap is adapted to seat flush upon the upper edge 33 of the bottle neck and be sealed thereto by a suitable cement 34.

The cap 25 is preferably dome-shaped (but not necessarily so) and is provided with an inverted U-shaped passage 35, an elongated extension 36 which opens into the chamber 37, between wall 22 of valve 21 and wall 26' of the cap. The foreshortened end 38 of passage 35 terminates above the upper wall 39 of an inclined tubular outlet 40, the end 41 of which projects slightly beyond the wall surface 42 of the cap. The wall 39 terminates short of the inner wall 43 of passage 35 which is returned inwardly to effect an entrance of said passage into the tube 40, which extends inwardly of the cap to beyond the vertical center thereof.

Following the outline of the passage 35 and inwardly thereof is a relatively small air passage 44, the inner end 45 of which also enters chamber 37, and the outer end 46 of which terminates slightly spaced from the inner terminal 46' of a similar air tube 47, the outer end 48 of which terminates with the end 41 of spout 40.

Upon inverting the bottle 11, the liquid therein will flow through valve seat opening 49 between the fluted passages 50, past unseated valve 15, through fluted passages 51, into chamber 37, and thence through passage 35 and tube 40, as indicated by arrows in Figure 2. However, the bottle can not be refilled due to the fact that if liquid could be gotten through the circuitous passage 35, it would be stopped by the heavy unfloatable valve 21, which valve could not be

displaced by a wire due to the arrangement of said passage 35. Furthermore, liquid would be stopped by an air lock at the juncture of passage 35, with inner tube end 52', for which the gap 52 between air passages 44, is provided.

From the foregoing specification it will become apparent that the invention disclosed will adequately accomplish the functions for which it has been designed and in an economical manner and that its simplicity, accuracy and ease of operation are such as to provide a relatively inexpensive device considering what it will accomplish and that it will find an important place in the art to which it appertains when once placed on the market.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described the invention that which is claimed to be new and desired to be procured by Letters Patent is:

1. The combination of a bottle having a neck with fluted inner walls and spaced valve seats, valves mounted on the seats, one valve being a float valve and the other a non-float valve, a cap having an outlet passage and being permanently fixed to the neck, together with means in the neck and upon the cap for permanent fixture of the cap on the neck, said passage being U-shaped, an inclined tube connecting therewith, an air passage for permitting air to enter the bottle, said cap having an annular flange sealed to the bottle neck, a gap in said air passage, said tube forming a spout and projecting beyond the outer surface of the cap.

2. The combination of a bottle having a neck with fluted inner walls and spaced valve seats, valves mounted on the seats, one valve being a float valve and the other a non-float valve, a cap having an outlet passage and being permanently fixed to the neck, together with means in the neck and upon the cap for permanent fixture of the cap on the neck, said passage being U-shaped, an inclined tube connecting therewith, an air passage for permitting air to enter the bottle, said cap having an annular flange sealed to the bottle neck, a gap in said air passage, said tube forming a spout.

3. The combination of a bottle having a neck with fluted inner walls and spaced valve seats, valves mounted on the seats, one valve being a float valve and the other a non-float valve, a cap having an outlet passage and being permanently fixed to the neck, together with means in the neck and upon the cap for permanent fixture of the cap on the neck, said passage being U-shaped, an inclined tube connecting therewith, an air passage for permitting air to enter the

bottle, said cap having an annular flange sealed to the bottle neck, and a gap in said air passage.

4. The combination of a bottle having a neck with fluted inner walls and spaced valve seats, valves mounted on the seats, one valve being a float valve and the other a non-float valve, a cap having an outlet passage and being permanently fixed to the neck, together with means in the neck and upon the cap for permanent fixture of the cap on the neck, said passage being U-shaped, an inclined tube connecting therewith, an air passage for permitting air to enter the bottle, said cap having an annular flange sealed to the bottle neck.

5. The combination of a bottle having a neck with fluted inner walls and spaced valve seats, valves mounted on the seats, one valve being a float valve and the other a non-float valve, a cap having an outlet passage and being permanently fixed to the neck, together with means in the neck and upon the cap for permanent fixture of the cap on the neck, said passage being U-shaped, an inclined tube connecting therewith, and an air passage for permitting air to enter the bottle.

6. The combination of a bottle having a neck with fluted inner walls and spaced valve seats, valves mounted on the seats, one valve being a float valve and the other a non-float valve, a cap having an outlet passage and being permanently fixed to the neck, together with means in the neck and upon the cap for permanent fixture of the cap on the neck, said passage being U-shaped, and an inclined tube connecting therewith.

7. The combination of a bottle having a neck with fluted inner walls and spaced valve seats, valves mounted on the seats, one valve being a float valve and the other a non-float valve, a cap having an outlet passage and being permanently fixed to the neck, together with means in the neck and upon the cap for permanent fixture of the cap on the neck, said passage being U-shaped.
